UNITED STATES PATENT OFFICE

1,979,736

VENTILATED TOILET

John H. Etter, San Francisco, Calif.

Application January 16, 1934, Serial No. 706,873

1 Claim. (Cl. 4—217)

The present invention relates to new and useful improvements in toilets and has for its primary object to provide, in a manner as hereinafter set forth, a device of the character embodying a novel construction, combination and arrangement of parts through the medium of which all objectionable odors will be drawn from the bowl.

Another very important object of the invention is to provide a ventilated toilet of the type including an exhaust fan driven by an electric motor, together with novel means for controlling the current to said motor.

Still further objects and advantages of the invention will become apparent from a study of the following specification, taken in connection with the accompanying drawings wherein like characters of reference designate corresponding parts throughout the several views, and wherein:

20 Figure 1 is a top plan view of a ventilated toilet constructed in accordance with the present invention.

Figure 2 is a view in vertical longitudinal section through the invention.

25 Figure 3 is a fragmentary view in vertical transverse section, taken substantially on the line 3—3 of Figure 1.

Figure 4 is a fragmentary view in vertical longitudinal section, taken substantially on the line 30 4—4 of Figure 3.

Figure 5 is a fragmentary view in horizontal section, taken substantially on the line 5—5 of Figure 4.

Figure 6 is a fragmentary view in side elevation, showing the mounting of the seat and cover.

Figure 7 is a horizontal sectional view, taken substantially on the line 7—7 of Figure 2.

Figure 8 is a diagrammatic view of the electric circuit.

40 Referring now to the drawings in detail, it will be seen that the embodiment of the invention which has been illustrated comprises a bowl 1 having its upper portion formed to provide a water channel 2 above which is formed a suction channel 3.

45 The water channel 2 is provided with outlet openings 4 in its lower portion and the suction channel 3 is provided with inlet openings 5 in its inner periphery. Of course, the channel 2 receives water from the usual flushing apparatus, as will be understood.

Rising from the rear portion of the bowl 1 is a pair of angular standards 6 to which a seat 7, of any suitable material, is hingedly connected by hangers 8. Also journaled between the standards 6 is a cover 9 for the seat 7. The seat 7 in-

cludes a body 10 which is split at its rear for the reception of a hollow insert 11. The insert 11 is preferably of metal and is secured in position by perforated wings 12 which are embedded in the adjacent end portions of the body 10. A sealing bead 12' depends from the body 10 of the seat 7 for engagement with the top of the bowl 1 when the toilet is in use. It will thus be seen that the body 10 of the seat, when in lowered position, will be spaced from the bowl 1.

Extending rearwardly from the upper portion of the bowl 1 is a suction conduit 13 having communication with the suction chamber 3 and the space between the body 10 of the seat and the bowl 1, as illustrated to advantage in Figure 2 of the drawings. Mounted on the forward portion of the suction conduit 13 is a substantially U-shaped gasket 14 with which the rear end of the insert 11 is engageable for providing a leak-proof joint between the seat 7 and said conduit 13 when said seat 7 is in lowered position.

Projecting rearwardly from the standards 6 are angular arms 15 upon which the springs 16 are mounted, said springs being operatively engaged with the seat 7 for yieldingly supporting said seat in slightly elevated position when the toilet is not in use, as indicated in broken lines in Figure 2 of the drawings. The arms 15 are provided with reduced free end portions (see Figures 3 and 5) which project through the gasket 14 and upon which insulated contacts 17 are mounted. From the foregoing it may be seen that the arms 15 may constitute means for supporting the resilient gasket 14 in position. The contacts 17 are engageable by the end portions of an insulated bridge member 18 which is mounted in the insert 11 of the seat 7. It will thus be seen that a switch, which is designated generally by the reference numeral 19, is provided for automatically controlling the exhaust fan motor, said motor being designated by the reference numeral 20 in Figure 8 of the drawings. Of course, one of the contacts 17 is electrically connected with the motor 20 while the other of said contacts is connected with a source of current supply.

Briefly, the operation of the invention is as follows:—

When the toilet is not in use the seat 7, as hereinbefore stated, is yieldingly supported in slightly raised or elevated position by the springs 16. With the seat in this position the motor 20 is deenergized, the switch 19 being open as the bridge member 18 is disengaged from the contacts 17. When the toilet is in use, the weight of the occupant depresses the seat 7 against the tension

100

105

110

of the springs 16 thereby closing the switch 19 for energizing the electric motor 20 and, of course, the exhaust fan, (not shown) is actuated. A suction is thus created in the chamber 3 and around 5 the top of the bowl 1 for drawing odors from said bowl, as will be readily understood. When the seat 7 is released the springs 16 will again raise said seat to the broken line position shown in Figure 2 of the drawings thereby opening the 10 switch 19 for deenergizing the electric motor 20. It is believed that the many advantages of a 15 ventilated toilet constructed in accordance with the present invention will be readily understood, and although the preferred embodiment of the invention is as illustrated and described, it is to be understood that changes in the details of construction and in the combination and arrangement of parts may be resorted to which will fall

within the scope of the invention as claimed. For example, with slight modifications the invention may be adapted for installation on toilet bowls which are already in use.

What is claimed is:—

A toilet comprising a bowl, a swingable seat, said bowl being provided with a passageway at the upper portion thereof opening at points with the interior of the bowl, a suction conduit connected to said bowl, a hinged connection between the seat and the conduit, means for raising the seat proper a slight distance above the bowl, the bowl end of the suction conduit being partly in communication with the said passageway and partly in communication with the space between the bowl and the seat.
